This application contains subject matter related to the following co-pending U.S. design patent applications:
Application Ser. No. 29/637,227, filed herewith and entitled “Front Bumper for a Vehicle”;
Application Ser. No. 29/637,228, filed herewith and entitled “Rear Fender for a Vehicle”;
Application Ser. No. 29/637,229, filed herewith and entitled “Tailgate for a Vehicle”;
Application Ser. No. 29/637,230, filed herewith and entitled “Rear Bumper for a Vehicle”;
Application Ser. No. 29/637,232, filed herewith and entitled “Taillight for a Vehicle”; and
Application Ser. No. 29/637,233, filed herewith and entitled “Taillight for a Vehicle”.

FIG. 1 is a left, front perspective view of a vehicle, toy, and/or replicas thereof according to the design;

FIG. 2 is a left side view thereof;

FIG. 3 is a right side view thereof;

FIG. 4 is a right, rear perspective view thereof;

FIG. 5 is a front view thereof;

FIG. 6 is a rear view thereof; and,

FIG. 7 is a top view thereof.
